UNITED STATES PATENT OFFICE.

JAMES A. DORAN, OF PROVIDENCE, RHODE ISLAND.

CUP-POST FOR ELECTRIC BATTERIES.

1,117,606.

Specification of Letters Patent. Patented Nov. 10, 1914.

Application filed July 3, 1913, Serial No. 777,266. Renewed June 15, 1914. Serial No. 345,292.

To all whom it may concern:

Be it known that I, JAMES A. DORAN, a citizen of the United States, residing at Providence, in the county of Providence and State of Rhode Island, have invented a certain new and useful Improvement in Cup-Posts for Electric Batteries, of which the following is a full, clear, and exact description.

10 Carbon sticks or pencils or pencil-like electrodes for electrical apparatus, have been provided with connecting posts in cup-form, the post itself being a separate piece riveted to the cup, but the post tends to 15 work loose from the cup in use, and the electrical connection is not always perfect owing to defective workmanship in applying the post to the cup, and also because of corrosion in the joint, such corrosion being increased by the loosening of the joint.

The object of this invention is to remedy these conditions, and to this end the invention consists in a cup-post in which the post is drawn up integrally with the cup.

25 In the accompanying drawings illustrating the invention, in the several figures of which like parts are similarly designated, Figure 1 is a perspective view of the integral cup-post, detached, and Fig. 2 is a cross-section showing part of the electrode in dotted lines.

The cup-post consists of a cup member 1 adapted to be frictionally fitted to the electrode 2, and this cup has the post 3 drawn

up from it integrally and screwthreaded. 35 In producing these cup-posts, a suitable metal blank is prepared, and then by suitable apparatus the post is drawn up to the proper length and of the required size, and the rim turned down to form the continuous 40 unbroken flange 4 of the cup by which the device is held in frictional engagement with the electrode. The post is then screw-threaded or otherwise prepared to receive the conducting wire or connection. The 45 cup-post may be made of any suitable material, such as brass or zinc. By this integral construction is avoided the working loose of the post, imperfect contact and other objections incident to the riveted-post construction, and the cost of manufacture, both in 50 material and labor, is greatly reduced.

What I claim is:

A cup-post for electrodes, comprising a cup having a continuous unbroken flange 55 adapted to engage the electrode frictionally, and a post drawn up from the material of the cup and in one integral piece therewith and adapted to receive an electrical connection.

In testimony whereof I have hereunto set my hand this 25th day of June A. D. 1913.

JAMES A. DORAN.
